ELECTRIC MASSAGER

Alfred W. Madl, Glendale, Wis., assignor to John Oster Manufacturing Co., Milwaukee, Wis., a corporation of Wisconsin

Filed Jan. 22, 1968, Ser. No. 10,258

Term of patent 14 years

(Cl. D83—1)

FIG. 1 is a perspective view of an electric massager embodying my new design;

FIG. 2 is a front elevational view thereof;

FIG. 3 is a side elevational view thereof;

FIG. 4 is a top plan view thereof; and

FIG. 5 is a bottom plan view thereof.

The broken line representations are for illustrative purposes only.

I claim:

The ornamental design for an electric massager, as shown and described.
